UNITED STATES PATENT OFFICE.

FLORINDA GARDNER, OF SALT LAKE CITY, UTAH.

PIANO-STOOL MUSIC-CABINET.

1,275,671.

Specification of Letters Patent. Patented Aug. 13, 1918.

Application filed January 23, 1918. Serial No. 213,321.

To all whom it may concern:

Be it known that I, FLORINDA GARDNER, a citizen of the United States, residing at Salt Lake City, in the county of Salt Lake 5 and State of Utah, have invented new and useful Improvements in Piano-Stool Music-Cabinets, of which the following is a specification.

My object is to make a piano stool or 10 bench having facilities for classifying and filing music so that it will be readily accessible to the operator.

Figure 1 is a perspective of a piano stool music cabinet embodying the principles of 15 my invention.

Fig. 2 is a vertical longitudinal sectional detail on the line 2—2 of Fig. 3.

Fig. 3 is a vertical cross-section on the line 3—3 of Fig. 2.

Fig. 4 is a fragmentary perspective illustrating the operation of removing or inserting one of the music pockets.

Fig. 5 is a view analogous to Fig. 4 and showing the connection between the music 25 pocket and the retaining rod.

Fig. 6 is a fragmentary sectional detail illustrating the connection between the follower board and the retaining rod.

The bottom boards 1 and 2 are mounted 30 horizontally upon legs 3, 4, 5 and 6 with the longitudinal slot 7 between the boards and at the transverse center, said slot extending from end to end of the boards. The side board 8 is fixed between the legs 3 and 4 35 and the side board 9 is fixed between the legs 5 and 6. The end board 10 is fixed between the legs 3 and 5 and the end board 11 is fixed between the legs 4 and 6 so as to make a rectangular box, the upper ends of 40 the legs 3, 4, 5 and 6 and the upper edges of the boards 8, 9, 10 and 11 being flush. A retaining rod 12 is mounted with its ends extending into the end boards 10 and 11 and said rod is centrally located in the slot 7 45 below the upper faces of the boards 1 and 2. The seat board 13 is adapted to cover one-half of the box and extend over the end board 10, and hinges 14 connect the outer end of the seat board 13 to the upper edge 50 of the end board 10, there being a projection 15 extending from the seat board outwardly beyond the hinge so that when the seat board is swung to and slightly beyond a vertical position the projection 15 will 55 engage the face of the end board 10 and hold the seat board in its upright position

so as to provide access to the interior. The seat board 16 is adapted to cover the other half of the box and extends beyond the end board 11 and is secured thereto by hinges 60 17, there being a projection 18 extending from the seat board beyond the hinges to engage the end board 11 and hold the seat board in its upright position.

A series of music pockets 19 is placed in 65 the box and held in upright position by a follower board 20. Each of the pockets 19 is adapted to receive a single class of music. In other words, there may be an independent pocket for each class of music and as many 70 pockets as there are classes of music. Each pocket is or may be constructed of stiff, tough paper and consists of a bottom 21, ends 22 and 23, and sides 24 and 25, the pocket being open at the top. The pockets 75 are considerably narrower than the width of the box between the side boards 8 and 9 and somewhat shorter than the height of the box and the pockets may be of any desired thickness and of a variety of thicknesses. A retainer 26 is secured upon each 80 pocket, each of said retainers comprising a rectangular attaching portion 27 adapted to be pasted or otherwise secured to the side of the pocket, and the extension portion 28 extending downwardly from the portion 27 below the plane of the bottom 21 and having a central opening 29 to approximately fit the rod 12, there being a slit 30 extending downwardly from the opening 29 to the 90 edge of the material so as to provide an entrance to the opening 29 and the edges 31 and 32 formed by the slit are preferably turned in opposite directions and the lower corners 33 and 34 are rounded outwardly, 95 so that when it is desired to insert a pocket 19 into the cabinet, the pocket is turned to a position substantially parallel with the rod 12 and guided downwardly so that the rod will engage the corners 33 and 34 and 100 bend the edges 31 and 32 in opposite directions and pass into the opening 29. Then the pocket is turned to a position transversely of the rod and the retainer holds the pocket slidably upon the rod, one object 105 being to hold the pocket down while a sheet of music is being pulled upwardly from the pocket.

The follower board 20 comprises a rectangular board 35 adapted to fit transversely 110 in the cabinet against a pocket 19, an ear 36 extending downwardly from the central

portion of the lower edge of the board through the slot 7, said ear having an opening 37 through which the rod 12 extends to hold the board from being withdrawn, 5 and a gripping brace 38 is secured to the board portion 35 to engage and grip the rod 12 and hold the follower board in an adjusted position against the pockets 19. The gripping brace 38 is formed of a strap of 10 spring metal and comprises the attaching portion 39, the bent spring portion 40 extending horizontally from the lower end of the portion 39, the portion 41 extending downwardly from the outer end of the portion 40 and slightly inclined toward the 15 board portion 35, and the clutching portion 42 extending from the lower end of the portion 41 into the slot 7, said clutching portion 42 being oppositely inclined relative to the portion 41 and there being an opening 43 through the portion 42 to receive the rod 12. The follower board is placed in the box with the rod 12 extending through the openings 37 and 43 and the lower edge of the 20 portion 35 resting upon the boards 1 and 2. When it is desired to move the follower board the brace 38 is engaged to spring the lower end of the portion 41 toward the board portion 35, thereby releasing the grip 25 of the brace upon the rod, and when the brace is released the tension of the metal will swing the portion 42 away from the board portion 35 and cause the rod 12 to cramp and grip in the opening 43 and 30 hold the follower board firmly against the pockets 19.

In the practical operation, the music will be suitably classified and placed in the pockets 19, the follower board moved against

the pockets to hold the pockets upright, and 40 when it is desired to obtain a piece of music the operator may sit upon the seat board 16 and raise the seat board 13, grasp the desired piece of music, and pull it from the pocket, the retainer 26 serving to hold the 45 pocket while the music is withdrawn. If the music is under the seat board 16 then the operator may sit upon the seat board 13 and raise the seat board 16.

Various changes may be made in the details of construction without departing from the spirit of my invention as claimed. 50

I claim:

In a piano stool music cabinet, two bottom boards spaced apart to form a slot, a lower board adapted to fit endwise upon the bottom boards and having an ear extending downwardly from its center into the slot, a spring metal attaching portion secured to the side of the follower board, a 55 bent spring portion extending horizontally from the lower end of the attaching portion, a second bent spring portion extending downwardly from the first bent spring portion and slightly inclined toward the follower board, a clutching portion extending from the lower end of the second bent spring portion into the slot and into the plane of the ear; there being a gripping opening through the clutching portion substantially 60 in line with the opening through the ear; and a rod mounted in the slot and extending through the opening in the ear and through the gripping opening.

In testimony whereof I have signed my 75 name to this specification.

FLORINDA GARDNER.
